UNITED STATES PATENT OFFICE.

MAX W. FISCHER, OF PORTLAND, OREGON, ASSIGNOR TO GILLEN-COLE CO., INCORPORATED, OF PORTLAND, OREGON.

SELF-CLOSING LATCH.

1,417,815.

Specification of Letters Patent. Patented May 30, 1922.

Application filed October 4, 1921. Serial No. 505,428.

To all whom it may concern:

Be it known that I, MAX W. FISCHER, a citizen of the United States, residing at Portland, in the county of Multnomah and 5 State of Oregon, have invented a new and Improved Self-Closing Latch, of which the following is a specification.

This invention has reference to improvements in latch mechanisms and more particularly to self-closing latches designed for being operatively mounted on refrigerator doors, fire doors, gas house doors or any other hinge doors where it is necessary that the doors close tightly against the door frame 15 or jamb, automatically.

Primarily my invention seeks to provide an improved construction of self-closing door latch, of a simple and inexpensive construction, in which the parts are conveniently arranged, durable, efficient, and which can be economically made and readily assembled to their operative connection with the door and door frame.

With other minor objects in view and 25 hereinafter apparent, my invention consists of a door latch of the general character mentioned that embodies the general construction and combination of parts fully explained in the following detailed description, 30 specifically pointed out in the appended claim and illustrated in the accompanying drawing, in which:

Figure 1 is a face view of my improved door latch, the same being shown operatively 35 applied to a portion of a swinging door and an adjacent frame portion.

Figure 2 is a plan view thereof with a part 40 of the door and door frame, the latter being shown partly in horizontal section and at an open position in dotted lines.

In the practical development of my invention, the same includes a latch post 1 of peculiar design that is mounted on the door frame or jamb 9 and with which the latch 45 bolt 4 cooperates in the manner presently explained.

50 5 designates a frame and it has ears which receive lag screws 8 that secure the said frame to the swinging door 11 and the 55 said latch post 1 has a base portion 10 that is provided with ears through which pass lag bolts 80 that secure the said post to the door jamb, as shown.

The latch bolt frame 5 has a pair of outwardly projected brackets 55—56, the rear

one 56 of which has an aperture 57 through which the inner end of the latch bolt 4 freely passes.

The outer end of the bolt 4 terminates in a bifurcated head 40, the inner or solid 60 portion of which passes through an elongated slot 58 in the outer bracket 55, such connection of the bolt and the bracket 55 operating to hold the bolt 4 from rotation within its bearing, as it is longitudinally reciprocated through the said brackets 55—56 in the manner presently explained.

7 designates a cotter key that engages the inner end of the bolt 4 and the adjacent face of the bearing 56.

A stout coil spring 6 is mounted around the bolt 4 with one end engaging the outer bracket 56 and the other or outer end held against the inner end 41 of the bolt head 40, as shown, it being understood that the 75 tension of the said spring 6 tends to normally force the bolt 4 outwardly to a latching position.

A roller latch 2 is journaled, on a cross bolt, in the bifurcated end of the bolt head, 80 and as clearly shown in the drawing, the said roller latch 2 is so positioned relatively to the flange edge 12 of the door that it at all times projects some distance beyond the said door edge and for moving into engagement with the latch post 1 when the door is 85 swung to its closing position.

The latch post 1, before mentioned, includes an outer beveled bearing face or track 13 that is disposed at such angle relatively 90 to the face of the door so as to cause the latch bolt 4, when brought into contact with the said face 13, to slide inwardly through its bearings 55—56 during the action of closing the door.

The latch post 1 is also provided with an inner bearing face or trackway 14 which face is disposed at an angle of approximately 45° to the face of the door frame or jamb and at the outer end the said trackway 14 merges with the inner end of the other beveled face or trackway 13.

As is apparent from Figure 2 of the drawing, when the door is closed (from the dotted line position) the latch roller 2 engages 105 the beveled outer bearing face 13 and thereby causes the bolt to slide back through the bearing apertures in the brackets 55—56, thereby storing tension in the spring 6 as the bolt is thus shifted.

As the roller latch 2 passes inwardly beyond the base of the bearing face 13, the tension of the spring 6 forces the said bolt and the roller latch 2 outwardly in the direction 5 of the arrow α on Figure 2 of the drawing and into a tight latching engagement with the inwardly inclined bearing face 14 of the latch bolt 4.

The angle of the face 14 and the tension of 10 the spring 6, and the latching end of the bolt being in the nature of a roller, provides for a constant outward pressure of the latch roller against the bearing track 14 and at the same time causes the said latch roller to 15 travel inwardly in the direction of the arrow γ and thereby tends to hold the door flange 12 to a tightly closed position.

The tension of the spring 6 moves the latch bolt in the forward limit of travel 20 which limit is fixed by the cotter key connection 7 and the rear bearing 56 of the latch bolt frame 5.

When the door is open the roller latch 2 travels up face 14 of the trackway on the post 25 1 pushing the bolt inwardly until it passes over the apex or juncture of the two faces 13 and 14, it being understood that so soon as the roller passes the said point the tension of the spring 6 now tends to force the roller 30 outwardly along the outwardly beveled face 13 of the post and assists the door to swing to the open position.

When the door is closed the pressure of the latch bolt, as before stated, tends to push the 35 latch roller 2 inwardly or down the face 14 of the post which pressure is transferred to the door and holds it tightly against the door jamb.

From the foregoing description taken in 40 connection with the drawings the complete construction, the manner of operation and advantages of this invention will be readily apparent to those familiar with the use of door latch devices together with the general character to which this invention relates.

While the action of the locking of the latch bolt is automatic, the arrangement of the latch bolt and bolt devices are such that

they tend to constantly clamp the door edge to a tight closure against the door jamb. 50 The door can be conveniently pulled open without the necessity of manipulating the latch devices, which devices are always in adjustment for automatically effecting the latching of the door when it is swung to its 55 closing position.

What I claim is:

As a new article, a door latch of the character stated comprising a frame adapted for being attached to a door edge, the said 60 frame including a pair of outwardly extending brackets, one at the inner and the other at the outer end of the frame, the inner bracket having an aperture, the bracket at the outer end having an elongated slot, a 65 latch bolt including a shank that slidably engages the apertured bracket and a non-circular bifurcated head that constantly rides within the non-circular slot in the outer bracket, a roller bearing mounted within the 70 bifurcations of the bolt head, a coil spring disposed upon the bolt, one end thereof engaging the inner end of the bolt head, the other end engaging an inner bracket of the latch frame, the said spring tending to normally thrust the bolt, with its roller bearing, beyond the edge of the door to which the latch may be attached, and a latch post, the 75 said post having a base portion to adapt it for attachment to the door frame or jamb, 80 the said post having an outer bearing surface inwardly beveled relatively to the door frame and adapted for being engaged by the latch bearing roller as the door is closed to thereby push the latch bolt back and store 85 tension in the spring, the said post having another bearing surface that is inwardly beveled relatively to the door jamb and whose outer end merges with the inner end of the other beveled surface whereby to receive the 90 bearing roller of the latch bolt and automatically swing the door with the bolt inwardly under tension of the spring to thereby cause the door to close tightly against the door frame or jamb.

M. W. FISCHER.
